(Cl. D3—13)

(Granted under Title 35, U.S. Code (1952), sec. 266)

Fig. 1.

Fig. 2

Fig. 4

Fig. 3.

FIGURE 1 is a front elevational view of a top for a cap stay embodying my new design;

FIGURE 2 is a bottom plan view thereof;

FIGURE 3 is an end elevational view thereof; and

FIGURE 4 is a top plan view thereof.

The fragmentary disclosure of a cap stay shown in broken lines in FIGURES 1 and 3 is for purposes of illustration only.

The invention described herein, if patented, may be manufactured and used by or for the Government for governmental purposes, without the payment to me of any royalty thereon.

I claim:

The ornamental design for a top for a cap stay, substantially as shown and described.
